Primary Examiner — Cynthia Ramirez

(57) **CLAIM**

The ornamental design for a trash can, as shown and described.

DESCRIPTION

FIG. 1 is a top perspective view of a trash can, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is the top perspective view of its open state;

FIG. 9 is the top perspective view with the top cover open; and,

FIG. 10 is another top perspective view with the top cover open.

The broken lines in the drawings illustrate the portions of the trash can, which form no part of the claimed design.
